UNITED STATES PATENT OFFICE

108,483

DESIGN FOR A LAUNDRY STOVE

John A. Underwood, Chicago, Ill., assignor to Montgomery Ward & Co., Incorporated, Chicago, Ill., a corporation of Illinois

Application July 15, 1937, Serial No. 70,465

Term of patent 7 years

To all whom it may concern:

Be it known that I, John A. Underwood, a citizen of the United States, residing at Chicago, in the county of Cook and State of Illinois, have invented a new, original, and ornamental Design for Laundry Stoves, of which the following is a specification; reference being had to the accompanying drawing, forming a part thereof.

In the drawing the figure is a perspective view of a laundry stove showing my new design, the side of the stove not shown being like the side illustrated.

I claim:

The ornamental design for a laundry stove, as shown and described.

JOHN A. UNDERWOOD.
